COMBINED BOTTLE OPENER AND CAN PIERCER

Vivian M. Brandow, 7828 SE. Johnson Creek Blvd.,
Portland, Oreg. 97206

Filed June 29, 1972, Ser. No. 267,691

Term of patent 14 years

Int. Cl. D7—99

U.S. Cl. D8—18

FIG. 1

FIG. 3

FIG. 2

FIG. 4

FIG. 1 is a plan view of a combined bottle opener and can piercer showing my new design.

FIG. 2 is a side elevational view of FIG. 1.

FIG. 3 is an elevational view of the right end of FIG. 1.

FIG. 4 is an elevational view of the left end of FIG. 2.

I claim:

The ornamental design for a combined bottle opener and can piercer, as shown.
